CLAIM

The ornamental design for an audio-radio-lighting device, as shown and described.

DESCRIPTION

FIG. 1 is a perspective left side view of an audio-radio-lighting device;

FIG. 2 is a perspective right side view thereof;

FIG. 3 is a perspective bottom view thereof with a hook in folded configuration;

FIG. 4 is a perspective bottom view thereof with the hook in unfolded configuration;

FIG. 5 is a front view of FIG. 3;

FIG. 6 is a back view thereof;

FIG. 7 is a left-side view thereof;

FIG. 8 is a right-side view thereof;

FIG. 9 is a top view thereof; and,

FIG. 10 is a bottom view thereof.

The broken lines shown in FIGS. 1-10 illustrate portions of the audio-radio-lighting device and form no part of the claimed design.
